[57] CLAIM

The ornamental design for a disposable bra, as shown and described.

DESCRIPTION

FIG. 1 is a front perspective view of a disposable bra showing my new design;

FIG. 2 is a top perspective view thereof, the bottom perspective view being a mirror image;

FIG. 3 is a front elevational view thereof shown in a flattened condition;

FIG. 4 is a front perspective view of an alternate embodiment of the design shown in FIG. 1;

FIG. 5 is a top perspective view of FIG. 4, the bottom perspective view being a mirror image; and,

FIG. 6 is a front elevational view of FIG. 4 in a flattened condition.

The portions of interior surfaces not shown or described of the disposable bra form no part of the claimed design.
